(57) **CLAIM**

The ornamental design for a conference device, as shown and described.

DESCRIPTION

FIG. 1 is a perspective view of a conference device showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is another perspective view showing unclaimed environment.

The broken lines shown illustrate portions of the conference device that form no part of the claimed design.

1 Claim, 8 Drawing Sheets
